UNITED STATES PATENT OFFICE

2,457,341

CRAVAT HOLDER

Leon J. Biagi, Rumford, R. I., assignor to Swank,
Inc., a corporation of Delaware

Application August 13, 1946, Serial No. 690,172

4 Claims. (Cl. 24—49)

1

This invention relates to a cravat holder for retaining a four-in-hand necktie in position on the shirt of the wearer.

It is desirable to provide some sort of a retainer for preventing the four-in-hand necktie from swinging in the wind. Such retainers, particularly if they hold the tie in position by forcing it against the shirt, hold the tie off to one side of a central position with reference to the center line of the shirt.

One of the objects of this invention is to provide a cravat holder which will retain the tie in position by pressing it against the shirt and yet will maintain the tie substantially centrally of the vertical center line of the shirt.

Another object of this invention is to definitely locate the cravat holder with reference to the edge of the shirt and yet permit the tie to be clamped against the shirt.

Another object of this invention is to clamp the back jaw of the cravat holder to the shirt while leaving the front bar or jaw of the cravat holder in a position to grip the tie and hold it in position on the shirt.

Another object of this invention is to provide a device which will be of simple construction and simple to manipulate.

With these and other objects in view, the invention consists of certain novel features of construction, as will be more fully described and particularly pointed out in the appended claims.

In the accompanying drawings:

Fig. 1 is a front elevation of a person wearing the cravat holder which is the subject of this invention;

Fig. 2 is a top plan view of the cravat holder;
Fig. 3 is a bottom plan view thereof;

Fig. 4 is a central longitudinal section of the cravat holder;

Fig. 5 is a perspective view of the two jaws of the cravat holder with my improved retaining device tongue member detached;

Fig. 6 is a perspective view of the tongue member forming a part of the retaining device by itself;

Fig. 7 is a perspective view looking at the back of the cravat holder with the parts in assembled position;

Fig. 8 is a section view on line 8—8 of Fig. 1;

Fig. 9 is a view similar to Fig. 8 showing a modified arrangement of the holder.

In proceeding with this invention, I superimpose upon the back jaw of a cravat holder a hook shaped tongue which will position the back jaw

with relation to the edge of the shirt and which together with the back jaw will grip the edge of the shirt while leaving the front jaw free to grip the necktie and hold it against the shirt. The tongue is resilient so that pressure will flex it in one direction but the inherent spring of the stock will move it back to gripping position.

With reference to the drawing, 10 designates the front bar or front jaw of the cravat holder 10 which is bent as at 11 with a rear jaw 12 extending back along the front jaw or bar 10. There is a sufficient resiliency by reason of the bend 11 so that when these jaws are moved apart they will move toward each other into gripping relation 15 with any piece of fabric placed between them.

The rear jaw 12 is slotted at 13 and notched on its opposite edges as at 14 and 15 at a point spaced from the slot. A tongue designated generally 16 is provided with a pair of arms 17 and 20 18 to be bent about the back jaw at the location of the notches 14 and 15 so as to hold this tongue fixedly in position at one end. The shank 19 of the tongue is enlarged as at 20 at one end and is cut out as at 21 by lifting the hook 22 from this portion of the stock. This hook has an abutment portion 23 and a portion 24 which extends generally parallel to the shank 19. This hook 22 will be so located as to pass through the slot 13 in the rear jaw and the entire tongue will be so arched as shown in Figs. 7 and 8 that the end portion 20 will engage the rear jaw 12 adjacent the bend 11.

In operation the center portion 24 of this tongue which is arched as shown in Figs. 7 and 8 is pressed inwardly which will space the portion 24 of the hook from the rear jaw 12. The edge 25 of the shirt may then be positioned into the hook and against the abutment portion 23 (see Fig. 8) and then the tongue released so that the hook portion 24 will press the edge of the shirt against the inner surface of the rear jaw 12 so as to securely bind it in position. A cravat 26 may then be positioned between the front jaw or bar 10 and the shirt being backed up by the main portion of the rear jaw 12. Thus the cravat will be held so that its opposite edges 27 and 28 will be centralized with reference to the center of the shirt which will be closely related to the edge of the shirt which is gripped by the hook portion.

In some cases the tongue 16 as shown in Fig. 9 is formed integrally with the rear jaw 12, it being formed by longitudinal slits extending from point 30 to a point 31 short of the end of the jaw 12, with the portion between the slits raised and

bent to form a hook as at 24' with abutment 23'.

I claim:

1. A cravat holder comprising a front bar, a rear jaw bent therefrom for reception and gripping of a cravat between them by the inherent resiliency of the material of which the holder is made, and means independent of the front bar and cooperating with the rear jaw to clamp the rear jaw to the edge of a shirt at a position located between the front bar and the rear bar.

2. A cravat holder as set forth in claim 1 wherein said means are so located intermediate the ends of the jaw that said jaw extends at both sides of the shirt edge a substantial extent.

3. A cravat holder as set forth in claim 1 wherein said means comprises a resilient tongue having a hook carried thereby to clamp the edge of a shirt against the forward face of the rear jaw.

4. A cravat holder as set forth in claim 1 wherein said means comprises a resilient tongue

mounted on the jaw distant from the bar and having a hook carried thereby, said rear jaw being slotted and said hook movable through said slot to grip the edge of a shirt and force the same against the opposite face of said rear jaw.
